UNITED STATES PATENT OFFICE

PAUL BUSTARD, OF FREDERICK, OKLAHOMA

CARBURETER

13,498.

Specification of Reissued Letters Patent. Reissued Dec. 15, 1913.

Original No. 965,867, dated August 2, 1910, Serial No. 537,550. Application for reissue filed October 28, 1910. Serial No. 589,820.

To all whom it may concern:

Be it known that I, PAUL BUSTARD, a citizen of the United States, residing at Frederick, in the county of Tillman and State of Oklahoma, have invented certain new and useful Improvements in Carbureters, of which the following is a specification.

This invention relates to carburetors of
10 that type in which air is forced through a
body of hydro-carbon contained in a ves-
sel which is connected to the engine, the appa-
ratus being designed more particularly
15 for use in connection with internal combus-
tion engines, although not limited to such
use.

The primary object of the invention is to provide a carbureter which is so constructed that it will be impossible to flood the engine with gasoline in a liquid state, and also to provide a carbureter in which a perfect mixture of air and hydro-carbon vapor is effected, thereby enabling the engine to start on the first complete cycle.

25 Another object of the invention is to provide a carbureter which shall include the principles of a surface carbureter, a filtration carbureter and a spray carbureter.

80 A still further object of the invention is to provide a carbureter in which the inrushing air caused by the suction stroke of the engine, shall cause a plurality of sprays of mixed liquid hydro-carbon and air to be delivered against a screen of absorbent fibrous material, thus charging the screen with liquid hydro-carbon whereby the air passing up through the screen shall become thoroughly impregnated with the hydro-carbon, the screen further acting both to break up 85 the particles of air and intimately mix the particles of gasoline therewith and to catch the surplus liquid hydro-carbon which is not combined with the air, thus causing the gas to be thoroughly dried before passing to the 90 engine.

Further object of the invention is to provide means whereby the liquid hydro-carbon thus caught by the screen shall be returned to the tank or reservoir from which it was ejected.

The invention also has for its object to provide a carbureter embodying certain novel structural details, resulting in greater

efficiency, as will be hereinafter described and claimed.

In the accompanying drawings forming a part of the specification, Figure 1 is a vertical section of a carbureter constructed in accordance with my invention. Fig. 2 is a horizontal section on the line 2—2 of Fig. 1.

In the drawings, 5 denotes the casing of the carbureter which forms a tank for containing the supply of gasoline or other hydro-carbon, the tank being provided with a filling tube 6 entering through the top 65 thereof, and provided with a suitable closure 7. In the tank is a false bottom 8 to form a water chamber 9, this chamber being located below the false bottom and the supply of gasoline being carried in the tank above 70 the false bottom. The water chamber is provided for the purpose of heating the gasoline to promote vaporization. Warm water is introduced into the chamber 75 through a pipe 10, and leaves the chamber through a pipe 11, the outlet and inlet ends of said pipe being located respectively adjacent to opposite ends of the chamber, whereby circulation is maintained therein.

Above the false bottom 8, the tank 5 contains horizontal partitions 12 and 13 respectively which are spaced from each other and connected by a series of spray tubes 14 opening therethrough. These spray tubes are preferably arranged in a circular series 85 though this arrangement is not absolutely necessary. One end of each tube 14 opens into the space between the partition 12 and the false bottom 8, and the other end of the tube opens into the space above the partition 13. 90

Located centrally within the tank and disposed between the partitions 12 and 13, is a perforated annular wall or tube 15. The diameter of this tube is considerably greater than the diameter of the tubes 14, and the latter extend in a circle around the same adjacent to the tank wall. The partition 12 is formed with perforations 16 which are located in the central part of the partition covered by the tube 15. The partition 13 has perforations 17 which extend throughout the entire area thereof, including that portion of the partition which is over the tube 15.

Above the partition 13, there is disposed 105

a screen 18 formed of absorbent fibrous material which is held between gratings of wire gauze. This screen 18 of absorbent material extends entirely across the interior of the tank and above the same is located a plurality of wire gauze screens 20 also extending entirely across the interior of the tank. The screen 18 is relatively thick and as it is made of fibrous material it will absorb gasoline.

Above the screens 20 an air supply tube 21 enters the tank 5. This tube is provided with a valve for controlling the amount of air entering the tank, said valve comprising a sleeve 22 mounted for rotation on the tube 21 and having an opening 23 adapted to more or less register with an opening 24 in the tube.

Below the air tube 21, the tank 5 is encircled 20 on the outside by an air chamber 25, said air chamber being mounted on the tank in any suitable manner and being annular in form. Entering this chamber are the air supply tubes 26, each provided with a valve 27 similar to the valve 22 already described. From the air chamber 25, ducts 28 lead into the tank 5 below the partition 12. A plurality of ducts 28 are provided preferably extending in a circular series around the 30 tank on the outside thereof. At the upper end of the tank is an outlet pipe 29 having a laterally directed branch 30 which is connected to the suction pipe 31 of the engine, (not shown). The pipe 29 is provided with 35 a relief valve 32 seating on a perforated diaphragm 33 located in the pipe 29 above the pipe 30. The upper end of the pipe 29 is closed by a perforated screw cap 34, and between this cap and the valve 32 is interposed a coil spring 35 for holding the valve seated.

In operation the tank 5 is filled with gasoline up to within a short distance from the partition 13. On the suction stroke of the 45 engine, air is drawn down the ducts 28 from the air chamber 25 into the gasoline, and then passes upwardly through the tubes 14 which are partly immersed in the gasoline, these tubes constituting inspirator tubes whereby 50 sprays of mixed air and gasoline are ejected against the screen 18. Particles of gasoline are carried upwardly with the air against the screen 18 which thus becomes saturated with gasoline, so that the air passing there-through is carbureted. Inasmuch as the 55 screen 18 is relatively thick the entire material of the screen will not be equally saturated with gasoline. The lower portion of the screen, that portion of the screen imme-diately adjacent to the inspirator tubes 14, 60 will receive the impact of the mixed air and gasoline and will be most fully saturated with gasoline, while succeeding layers of material will be less and less saturated. As 65 the charge passes up through the screen the

surplus gasoline will be entirely absorbed or taken up therefrom and the charge left in a dry state. If the air has not taken up sufficient gasoline in its progress from the air inlet opening in the reservoir through 70 the inspirator tubes, then it will absorb gasoline from the lower portion of the fibrous screen 18. The screen thus acts to render uniform the amount of gasoline taken up by the air. The carbureted air 75 passes through the screens 20 and is thoroughly mixed thereby, and upon meeting the incoming current of air entering the tank through the tube 21, commingles therewith and passes in a relatively dry state to the 80 engine. The screen 18 takes up any surplus liquid gasoline so that the gas created by the passage of air and gasoline through the screen 18 will be entirely dried. The valves 85 22 and 27 will be set to admit a proper volume of air, and after they are set, the engine may be started any number of times without further adjustment.

The surplus gasoline which is detained by the screen 18 eventually drips down onto the 90 partition 13 which forms a drainage plate. The liquid gasoline gathered on this plate passes through the perforations 17 and back into the supply. It will be seen that the gasoline is mixed and broken up initially 95 by being thrown up against the absorbent screen and the wire gauze and that it is also mixed and broken up when dropping back upon the drainage plate and in passing through the perforations 17. The perforations 17 are flared in the direction of the screen 18 and thus their diameter is relatively small at their lower ends, so that while the unused gasoline can drip down through the tank bottom it is prevented 100 from being thrown up against the screen 18 through the perforations 17.

The perforations in the tube 15 permit the gasoline to be maintained at the same level within the tank and permit the gasoline to 110 pass into the lower portion of the tank below the partition 12. At the same time the perforations in the bottom of the partition 12 and in the wall of the pipe 15, being small prevent the gasoline from being thrown up 115 upward and against the screen 18 by oscillations of the carburetor due to the movement of the mechanism to which it is attached. The wall 15 also performs another function, in that by dividing the interior of 120 the tank below the partition 13, violent agitation or oscillation of the liquid gasoline in the bottom of the tank is prevented or minimized.

It will be seen that I have provided a 125 carburetor in which a reservoir is provided and a carbureting chamber superposed upon the reservoir, the carbureting chamber and reservoir being separated from each other by a perforated partition, which by permit- 130

ting the drainage of surplus gasoline back into the reservoir, prevents waste. This perforated partition also prevents gasoline from being splashed upon the screen 18. It 5 will also be seen that in my carbureter the air entering through the ducts 28 passes through a body of gasoline and is forced up through the inspirating tubes 14 and carries with it sufficient hydro-carbon to properly 10 moisten the fibrous screen 18. This fibrous screen acts not only to break up and intermingle the particles of air and gasoline, but also to detain any surplus gasoline and hence the charge which passes into the upper 15 portion of the tank 5 and is mixed with air therein has been perfectly carbureted, uniformly mixed and thoroughly dried.

A carbureter constructed as herein described makes it impossible to flood the engine with gas having globules of liquid gasoline therein, and the engine consequently runs cool and develops a maximum amount of gas with a minimum of liquid hydro-carbon. The resultant pure, dry gas 25 prevents carbon deposits on the cylinder and cylinder head and reduces friction to a minimum. The apparatus is very simple in construction, all gasoline pumps, float feeds and needle valves being dispensed with, and 30 there being no movable parts to get loose or out of order. The efficiency of the apparatus is not affected by water or other impurities in the gasoline as the screen 18 and screen 20 separate the same.

35 To the bottom of the tank 5 is connected a pet cock 37 for drawing off the gasoline when it is desired to empty the tank and to clean it of impurities.

While my apparatus has been designed 40 for use on internal combustion engines, it is of course to be understood that it may be used for any other apparatus wherein a carbureter is needed.

What I claim is:

45 1. In a carbureter, a reservoir, a superposed carbureting chamber, a screen of fibrous material extending across the carbureting chamber, a perforated partition extending across the reservoir and below the 50 level of the liquid therein, inspirator tubes extending through said partition with their upper ends above the liquid level in position to discharge a spray of mixed hydro-carbon

oil and air against the lower face of the screen, and means for directing air into the 55 reservoir below the partition.

2. A carbureter comprising a tank, spaced partitions in the tank, a perforated tube mounted between the partitions, one of said partitions being perforated throughout its 60 entire area, and the other partition having perforations in its part which is covered by the aforesaid tube, imperforate tubes extending between the partitions and opening therethrough, air supply pipes entering the 65 tank below the partitions, and a screen of absorbent material located above the aforesaid partitions.

3. A carbureter comprising a tank, spaced partitions in the tank, tubes extending between the partitions and opening therethrough, an annular air chamber encircling the tank on the outside thereof, valve-controlled inlets to the chamber, pipes leading from the chamber into the tank below the 75 partitions, and a screen of absorbent material above the aforesaid partitions.

4. A carbureter comprising a tank, spaced partitions in the tank, one of said partitions being perforated, a perforated tube mounted 80 between the partitions, and opening therethrough, and imperforate tubes extending between the partitions and opening therethrough, air supply pipes entering the tank below the partitions, and a screen of absorbent material located above the uppermost partition.

5. A carbureter comprising a tank, spaced partitions in the tank, a perforated tube mounted centrally between the partitions, 90 one of said partitions being perforated throughout its entire area, and the other partition having perforations in its part which is covered by the aforesaid tube, a circular series of imperforate tubes extending 95 between the partitions around the perforated tube, and opening through said partitions, air supply pipes entering the tank below the partitions, and a screen of absorbent material located above the partitions.
